UNITED STATES PATENT OFFICE

ELBERT LETCHER MARKS, OF WASHINGTON, DISTRICT OF COLUMBIA

ANCHORING DEVICE FOR ARTICLE CONTAINERS

Application filed October 14, 1929. Serial No. 399,583.

This invention relates to article containers and more particularly to a receptacle or container into which bottles of milk, butter, groceries, mail, newspapers, packages of groceries, etc., may be placed and retained, until removed by the occupant of the house at which the container is installed, and the invention has as one of its objects to provide a container which, after the articles deposited therein have been removed, may be readily separated and removed from the door and its frame, or the window and its frame, the container being designed for use in connection with doors, windows, and trap doors, so that, when it is not in place for the reception of articles, it will not interfere with the opening and closing of the door in the customary manner. The complete assembly does not block the doorway and nothing is fastened to the door-frame.

Another object of the invention is to provide a receptacle or container of the class described, so constructed that it may be employed in connection with house doors having sills and also in connection with doors which do not have sills.

Another object of the invention is to provide means whereby a holding or retaining member, which is connected with the body of the container, may be folded to occupy a position beside the said body of the container when the container is not in use, so that the device will at such time occupy minimum space.

Another object of the invention is to provide means whereby a receptacle or container may be installed in position to receive the articles delivered to the house or store by the mere insertion of a retaining member between the lower edge of the door and the door sill, or the floor, where a sill is not present, this member preventing the receptacle or container being bodily carried away.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view in side elevation of the receptacle or container embodying the invention, the retaining or holding means for the container being shown in engagement between the lower edge of a door and its sill and the said door and sill being shown in section, the view also illustrating a bracing means for the container, and likewise illustrating in dotted lines the folded condition of the said retaining member.

Figure 2 is a view in rear elevation of the container, the holding means being shown in lowered position depending from the container.

Figure 3 is a top plan view of the rear portion of the container and showing the retaining member in position for insertion beneath the lower edge of the door.

Figure 4 is a detail view illustrating the means for connecting the bracing means of the invention with the container.

Figure 5 is a view illustrating a form of the invention in which the same is to be employed in connection with a door not provided with a sill.

Figure 6 is a top plan view of the embodiment shown in Figure 5.

The container 1, preferably made of sheet metal, is of rectangular form and of any desired depth and width dimensions, and the container is closed on all sides except at its top and a closure 2 is hinged at its rear side as at 3 to the upper edge of the rear wall of the body of the container and may be held closed by a lock 4 of a type to lock automatically after the closure has been once swung to open position and goods have been deposited therein and the closure again swung to closed position.

In the embodiment of the invention shown in Figures 1 and 2 of the drawings, the retaining member for the container is indicated by the numeral 5 and comprises a plate, which may be of the frusto-triangular form shown,

for example, in Figure 2 and likewise in a modification shown in Figure 3.

At its forward edge the retainer plate 5 is rolled or overturned to provide spaced longitudinally extending hinge sleeves 6, and a pintle rod 7 is inserted through these sleeves and through rectangular loops 8, which are riveted or otherwise secured at their upper ends as at 9 to the rear wall of the container 10 and at their lower ends to the bottom of the container. The outer or rear end of the retainer plate 5 is rolled upon itself to form a cylindrical abutment member, indicated by the numeral 11, and by reference to Figure 15 1 of the drawing, it will be observed that when the container is set up for use, the retainer plate 5 is disposed to rest upon the sill 12 for the door 13, and the door is then swung to closed position, the plate 5 being shifted as the door is being closed, so as to cause the abutment member 11 to bear against the inner side of the door at the lower edge thereof. At this point, it will be evident that inasmuch as the end and intermediate 20 portions of the pintle rod 7, of this arrangement of the parts, rests in the upper ends of the loops 8, the retainer plate 5 will constitute a means for supporting the container 1 and, in order that the container may be supported in upright position parallel to the door, it is formed in its rear wall with an opening 14 and a chain or cable 15 is provided with an eye 16 at one end, the eye resting against a washer 17, which is of metal 30 and is preferably disposed against a heat insulating lining 18, which is applied to the inner surface of the walls of the container.

The door is provided with an opening 19 which may be bored therein by any ordinary 40 boring drill, and a chain 15 is adapted to be led through this opening, and has pivoted to its end, an anchoring element, indicated by the numeral 20, which element comprises a head portion 21, and a finger portion 22, 45 the chain being connected to the element intermediate the ends thereof so that the portion 21 of the element will extend at a slight angle away from the door when the element is in the anchoring position shown in Figure 1. 50 This anchoring element, together with the chain 15 constitutes also a further means for preventing surreptitious removal of the container, and it will be understood at this point by reference to Figure 1 that the anchoring element may be tilted inwardly from the door and turned to position in alignment with the chain 15, and then slid through the opening 19, in disconnecting the chain and anchoring element from the door. In order that the 60 retainer plate 5 may be held in a folded position, as shown in broken lines in Figure 1 of the drawings, a substantially semi-circular clip 23 is mounted upon the rear wall of the container and is of resilient metal so as to 65 frictionally grip and hold the overturned

abutment portion 11 of the retaining plate, when engaged therein.

It will be understood that due to the oblong shape of the loops 8, the ends and intermediate portions of the pintle pin 7 may have 70 engagement in these loops at different points in the height thereof, and therefore the retaining device is effective for sills of various heights.

In order that display cards or a card bearing memorandum of the goods to be delivered to the user of the device may be fitted in the receptacle and retained in place, two channelled guides 24 are provided upon the upper side of the hinged cover 2 of the receptacle or they may be arranged upon the ends of the front thereof. 75

These cards may be instruction or advertising cards, in the latter instance, relating to dairies and, for example, bearing requests for return of empty bottles. 80

In the embodiment of the invention shown in Figures 5 and 6, the receptacle is intended for use in connection with a door which moves over the floor surface, where there is absence of a sill, and in this embodiment the retaining plate, which is in these figures indicated by the numeral 25, is directly hinged as at 26 to the rear wall of the receptacle at 90 the bottom thereof. 95

What I claim is:—

1. A receptacle, vertically disposed loops arranged on one side of the receptacle immediately adjacent the bottom thereof, a retaining plate having spaced longitudinally extending hinge sleeves along one edge, a pintle received by said sleeve and by said vertically disposed loops, whereby the retaining plate is capable of being arranged horizontally across the sill of a doorway, and adjusted in said loops for sills of various heights, and an abutment formed on the opposite longitudinal edge of the plate for engagement against the inner side of the door when the latter is closed. 100

2. A receptacle, a retaining plate hingedly mounted and vertically adjustable adjacent the bottom of the receptacle and adapted to be arranged horizontally across the sill of a doorway, an abutment formed on one edge of the plate and adapted to engage against the inner side of the door when the latter is closed, a chain slidable through an opening in one wall of the receptacle and adapted to be passed through an opening in the door, and an anchoring member pivoted on one end of the chain to be passed through the opening in the door and subsequently arranged parallel and in contacting engagement with the inner side of the door. 110

In testimony whereof I affix my signature.
ELBERT LETCHER MARKS.
